UNITED STATES PATENT OFFICE.

HARRY SPENCE, OF SANFORD, MAINE, ASSIGNOR OF ONE-FOURTH TO LOUIS B. GOODALL, ONE-FOURTH TO GEORGE B. GOODALL, AND ONE-FOURTH TO JOSEPH HOLLINRAKE, OF SANFORD, MAINE.

SPINNING-FRAME.

No. 806,016.

Specification of Letters Patent.

Patented Nov. 28, 1905.

Application filed October 9, 1902. Serial No. 126,407.

To all whom it may concern:

Be it known that I, HARRY SPENCE, a citizen of the United States, residing at Sanford, in the county of York and State of Maine, have invented an Improvement in Spinning-Frames, of which the following description, in connection with the accompanying drawings, is a specification, like characters on the drawings representing like parts.

The invention to be hereinafter described relates to spinning-spindles of the type wherein a flier is employed to put the desired twist into the yarn and thereafter wind it upon the bobbin. In such constructions the speed of the flier determines the amount of twist put into the yarn, and the bobbin is usually driven to wind the yarn made by the flier. Usually a spindle carrying and driving a flier has its upper bearing below the base of the bobbin, and such spindles driven at very high speeds are apt to gyrate by reason of the free upper ends, and thereby vary the tension on the yarn being spun and wound, such variations in tension resulting in the production of uneven and kinky yarn, and frequently the yarn is broken. To remedy these evils, I have provided for the spindle a top guide located above the top of the flier.

That the bearing for the upper end of the spindle may not interfere with the quick threading of the flier I have provided the upper end of the spindle with a thread-guiding disk, and the edges of the disk coact with the inner side walls of the top guide for the spindle.

The top guide referred to is open next the operator, so that the latter when about to thread up the flier may readily insert the yarn into a suitable notch in the edge of the disk referred to and pass the yarn behind a hook that acts to retain the yarn in the proper relation to the top of the spindle to insure proper twisting.

Figure 1 in side elevation and part section shows a spindle and its attached flier and adjacent parts embodying one form of my present invention. Fig. 2 is a top or plan view to more clearly illustrate the top guide for the spindle.

In the drawings, *a* represents a spindle having a pulley *a'*, by means of which it may be driven, as usual, from any convenient source of power, the step or lower bearing of the

spindle not being shown. Said spindle is properly supported by the spindle-rail *e*⁵ by means of the usual guide-bearing *e*. (See Fig. 1.) The bobbin *e*³ is carried by a tube *a*^x, which it fits adhesively, whereby upon rotation of the tube *a*^x upon the spindle *a* the bobbin may be properly rotated, a whirl or pulley *a*³, connected to the tube, serving to drive it by a band in usual manner. The top of the spindle above the bobbin-carrying tube is slabbed off and left preferably rectangular, and this part has slipped upon it a bushing *e*⁶, having a hole of corresponding shape, and upon external threads of this bushing (see Fig. 6) the hub of the flier *e*⁷ is screwed tightly.

The upper end of the bushing *e*⁶ is extended sufficiently above the upper side of the hub of the flier to have forced upon it a disk *a*⁶, (represented in Fig. 7 as slotted at 4,) that the threads may be readily introduced behind the stops 5, carried by the disk. The periphery of this disk coacts with the inner wall 6 of the open guide *f*, constituting a top bearing for the spindle. This top guide is represented as a plate open at its front side, and the shank of the plate is represented as 80 slotted to receive suitable set-screws 8, employed to hold the bearing in adjusted position.

In the operation of spinning the periphery of the disk revolves in its seat made in the top guide *f*, and this guide prevents any gyrations or vibrations of the upper end of the spindle.

I believe that I am the first to provide a spindle above the point of connection with it of the flier with an independent bearing. I have provided (see Fig. 6) an oil-cup *f*², by which to supply oil to the contacting face 6 of the top guide.

The spindle-rail *e*⁵ and step of the spindle (not necessary to illustrate) are mounted as usual to permit the spindle to be moved from the top guide *f* for doffing. In this position the disk *a*⁶ at the upper end of the spindle will be removed from the open mouth of the top guide *f*, permitting the flier to be readily removed from the upper end of the spindle, and thereafter the bobbin may be removed from the bobbin-tubes and the free ends of the spindles.

Having described my invention, what I

claim, and desire to secure by Letters Patent, is—

1. A spindle having a flier detachably fixed thereto at its upper end, a disk also detachably fixed to the upper end of the spindle, and a fixed guide embracing said disk and within which the disk may revolve to prevent gyration of the spindle at high speed.

2. In a spinning-frame, a spindle having a flier fixed to its upper end, and also a disk having an opening through which the material being spun may be led about the flier-leg to the flier-eye on its way to the bobbin, and a guide embracing said disk to prevent gyration of the spindle at high speed.

3. In a spinning-frame, a spindle having an attached flier, a slotted disk rotatable with the spindle and provided with a stop, and a bearing fitting the exterior of said disk and steadyng the spindle in its rapid rotation.

4. A spindle having a flier fixed thereto at its upper end, a disk also fixed to the upper end of the spindle, and an open guide constituting a top bearing for the spindle and embracing said disk to steady the upper end of the spindle at high speeds.

5. A spinning-spindle having a flier fixed thereto at its upper end, a disk rotatable with said spindle and provided with stops for engagement with the yarn or thread, and a fixed bearing fitting the exterior of said disk and steadyng the spindle in its rapid rotation.

In testimony whereof I have signed my name to this specification in the presence of two subscribing witnesses.

HARRY SPENCE.
